CLAIM

The ornamental design for a graphics tablet, as shown and described.

DESCRIPTION

FIG. 1 is a front-right-top perspective view of a graphics tablet according to my new design;

FIG. 2 is a rear-left-bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is an enlarged partial front-right-top perspective view thereof as indicated in FIG. 1; and,

FIG. 10 is an enlarged partial top plan view thereof as indicated in FIG. 7.

The dashed indicator lines enclosing area "9" in FIG. 1 and area "10" in FIG. 7 are for reference to the enlarged views only and form no part of the claim. The dash-dot-dot broken lines in FIGS. 9 and 10 show the extent of the enlarged views only and form no part of the claim. All other broken
